UNITED STATES PATENT OFFICE.

WILLIAM WILLHEIM, OF NEW YORK, N. Y., ASSIGNOR TO FRANK & COHEN SILK CORPORATION, A CORPORATION OF NEW YORK.

DESIGN FOR A TEXTILE FABRIC OR SIMILAR ARTICLE.

Application filed October 11, 1928. Serial No. 28,464. Term of patent 3½ years.

To all whom it may concern:

Be it known that I, WILLIAM WILLHEIM, a citizen of the United States, residing at city of New York, in the county of New York and State of New York, have invented a new, original, and ornamental Design for a Textile Fabric or Similar Article, of which the following is a specification, reference being had to the accompanying drawing and to the accompanying sample of goods bearing the design, forming a part thereof.

The figure on the drawing is a plan view of a piece of textile fabric bearing my new design which is intended to be carried for-

ward or repeated ad libitum, as shown. The shading is on the drawing only to indicate more or less contrasting colors and not to indicate specific colors.

The unit of my design is delimited on the drawing by the indicating arrows 1 and 2. The upper corners of this unit are shown repeated in the angles formed by indicating arrow 3 with the arrow 1.

I claim as my invention :

The ornamental design for a textile fabric or similar article, substantially as shown and described.

WILLIAM WILLHEIM.
